GARMENT PROTECTOR

George Aranow, New York, N. Y., assignor to
 Richards, Boggs & King, Inc., Chicago, Ill., a
 corporation of Delaware

Application June 16, 1941, Serial No. 398,193

3 Claims. (Cl. 223—98)

The present invention relates generally to garment protectors. More particularly the invention relates to that type of protector which is shaped and designed to fit over and cover the shoulder portion of a lady's dress or like garment on a hook-equipped clothes hanger and comprises complementary or substantially similarly shaped front and back pieces which are formed of "Pliofilm" or like thin transparent material are joined together along the top and side margins thereof by way of a binding strip of U-shaped cross section and a line of stitching, and together form a transparent hood whereby the shoulder portion of the dress over which the protector is used is readily visible and is protected against dust as well as soiling or injury due to handling.

In fabricating or producing a garment protector of this type it has heretofore been customary to leave the central portions of the top margins of the front and back pieces disconnected in order to form a slit-like aperture at the top of the protector for accommodating the hook of the hanger over which the protector is used. It has also been customary to have the central portion of the binding strip overlie and extend along the central or aperture defining portion of the top margin of the back piece for purposes of reenforcement, and in addition to reinforce the central or aperture defining portion of the top margin of the front piece by way of a short separate binding strip of U-shaped cross section and a row or line of stitching. In practice it has been found that a garment protector made in accordance with the aforementioned method of manufacture is deficient or objectionable for the reason that when pressure or force is exerted on the aperture defining portions of the front and back pieces in connection with insertion of the hanger hook through the aperture or withdrawal of the hanger from the protector the stitching at the wedge or U-shaped junctures of the ends of the short separate binding strip along the central or aperture defining portion of the top margin of the front piece with the adjacent portions of the main binding strip in most instances breaks and this in turn results in an objectionable elongation of the slit-like aperture for the hanger hook and tearing of the "Pliofilm" or other transparent material of which the front and back pieces of the protector are formed.

The primary object of the instant invention is to provide a garment protector of the type under consideration which is an improvement upon, and eliminates the objectionable points or fea-

tures of, previously designed garment protectors for the same general purpose by reason of the fact that the aperture defining margins of the front and back pieces instead of being conventionally reenforced are reenforced by a single binding strip which is of U-shaped cross section, extends around the aperture defining margin portions of both front and back "Pliofilm" pieces and has its ends arranged in overlapped relation at the central portion of the top margin of either of the two pieces. By employing a single binding strip of this type or character there is a continuous reenforcement around the hook receiving aperture and there is no likelihood or possibility of the protector splitting, rupturing or breaking at the ends of the aperture when the aperture defining top margins of the front and back pieces are separated or pulled apart in connection with insertion of the hanger hook through the aperture or removal of the hanger from the protector.

Another object of the invention is to provide a garment protector of the last mentioned type and character in which the side reenforcement, that is, the reenforcement for the side margins and outer portions of the top margins of the front and back pieces is in the form of a pair of binding strips which are stitched in place and have the upper ends thereof fitting within the portions of the aperture reenforcing binding strip that define the ends of the aperture to the end that the portions of the protector at the ends of the aperture are additionally reenforced against breaking or rupture.

A further object of the invention is to provide a garment protector which is generally of new and improved construction and not only may be made and produced at a low and reasonable cost but also is extremely durable and well suited for its intended purpose.

Other objects of the invention and the various advantages and characteristics of the present garment protector will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective view of a garment protector embodying the invention;

Figure 2 is a fragmentary perspective view

showing the upper central portion of the protector before application of the aperture reenforcing binding strip;

Figure 3 is a perspective view of the single binding strip for reenforcing the entire aperture defining portions of the front and back pieces of the protector;

Figure 4 is a fragmentary perspective view showing the upper central portion of the protector after application of the aperture reenforcing binding strip;

Figure 5 is a horizontal section taken on the line 5—5 of Figure 4 and illustrating in detail the manner in which the upper ends of the side binding strips fit within and are anchored to the portions of the aperture reenforcing binding strip that are at the ends of the aperture; and

Figure 6 is a vertical section taken on the line 6—6 of Figure 4 and showing the cross sectional design or construction of the aperture reenforcing binding strip.

The protector which is shown in the drawing constitutes the preferred form or embodiment of the invention. It is designed to fit over and cover the shoulder portion of a lady's dress or other garment on a hook equipped clothes hanger and serves in the capacity of a shield or hood to protect the garment against dust as well as soiling or injury due to handling. As its primary or principal parts the protector comprises a front piece 7 and a back piece 8. These two pieces are similar in shape and design and are positioned one in front of the other, as shown in Figure 1. They are formed of "Pliofilm" or like thin transparent material so that the protector as a whole is transparent and the user is hence able to see the shoulder portion of the garment with which the protector is used. The bottom edge or margin of the front piece is straight and a longitudinally extending binding strip 9 is associated with it for reenforcing purposes. The strip 9 is centrally folded so that it is of U-shaped cross section and extends from one end of the bottom margin of the front piece 7 to the other. It is arranged in straddled relation with said bottom margin of the front piece and is held in place by means of a row or line 10 of stitching. The side margins of the front piece 7 are substantially straight and the top margin is curved or arched. The back piece 8 of the protector is in the form of a complement and it also has a straight bottom edge or margin which is reenforced by a binding strip of U-shaped cross section and a line or row of stitching (both not shown). The side margins and the outer portions of the top margins of the front and back pieces are secured together and reenforced by way of binding strips 11 and rows or lines 12 of stitching. The binding strips 11 are bent centrally and longitudinally so that they are of U-shaped cross section and straddle the adjacent marginal portions of the front and back pieces. The lower ends of the binding strips 11 terminate adjacent the lower corners of the protector and the upper ends of the strips terminate adjacent the central portions of the top margins of the pieces. As shown in the drawing, the central portions of the top margins of the front and back pieces are disconnected so as to form a slit-like aperture 13 at the top of the protector. This aperture, as well understood in the art, is adapted to receive or accommodate the hook of the clothes hanger to which the protector is applied. For the purpose of reenforcing the marginal portions of the front and back pieces that define the hook re-

ceiving aperture 13 a binding strip 14 is provided. This binding strip is formed of "Pliofilm" or other tough durable flexible material and is folded centrally and longitudinally so that it is of U-shaped cross section. The central portion of the binding strip 14 extends along, and is arranged in straddled relation with, the aperture defining portion of the top margin of the back piece 8. The ends of the binding strip are folded or bent inwards and are arranged so that their extremities are in telescopic relation. They are arranged in straddled relation with the aperture defining portion of the top margin of the front piece 7 of the protector and serve as a reenforcing medium for such portion. A continuous row or line 15 of stitching serves to anchor the binding strip 14 in place. The folded or curved end portions of the binding strip reenforce the ends of the slit-like hook receiving aperture 13 and overlie and surround the upper ends of the binding strips 12, as shown in Figure 5. Portions of the stitching which serve to anchor the binding strip 14 in place pass through the upper ends of the binding strips 11 and thus connect such ends to the curved or folded portions of the binding strip 14. Said upper ends of the binding strips 12 are bent or twisted so that they fit within the curved or folded portions of the binding strip 14. When the binding strip 14 is in place it is continuous and serves not only effectively to reenforce the aperture defining portions of the top margins of the front and back pieces 7 and 8 but also the portions of the protector at the ends of the aperture 13. By reason of the fact that the reenforcement is continuous at the ends of the slit-like aperture 13 there is no likelihood of the protector breaking or rupturing at the ends of the aperture when the aperture defining portions of the top margins of the front and back pieces are pulled apart in connection with insertion of the hanger hook through the aperture or removal of the hanger from the protector. The binding strips 11 are preferably formed of the same material as the aperture reenforcing binding strip 14.

The herein described garment protector may be manufactured at a low and reasonable cost and is characterized by the fact that it is extremely durable due to the manner in which the hook aperture is reenforced by the binding strip 14.

Whereas the invention has been described and illustrated in connection with a garment protector of the shoulder covering variety or type it is to be understood that it also may be employed in connection with full length garment bags or like garment protectors. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. As a new article of manufacture, a protector adapted to be placed over, and to protect, the shoulder portion of a garment on a hook equipped clothes hanger and comprising similarly shaped front and back pieces positioned one in front of the other and having their side margins and the outer portions of their top margins joined together and also having the central portions of the top margins thereof substantially straight and disconnected to form a slit-like aperture for

receiving the hook of the hanger, and a continuous binding strip of U-shaped cross section extending around and in straddled relation with, and anchored to, the aperture defining portions of said front and back pieces, and serving to reinforce the last mentioned portions and prevent rupture of the protector at the ends of said aperture.

2. As a new article of manufacture, a protector adapted to be placed over, and to protect, the shoulder portion of a garment on a hook equipped clothes hanger and comprising similarly shaped front and back pieces positioned one in front of the other and having their side margins and the outer portions of their top margins joined together and also having the central portions of the top margins thereof substantially straight and disconnected to form a slit-like aperture for receiving the hook of the hanger, and an elongated one-piece binding strip of U-shaped cross section extending around and in straddled relation with, and anchored to, the aperture defining portions of said front and back pieces, having the ends thereof arranged in telescopic relation at a point other than the ends of the aperture, and serving to reinforce said aperture defining portions of the front and back pieces and also to prevent rupture of the protector at the ends of said aperture.

3. As a new article of manufacture, a protector adapted to be placed over, and protect the shoulder portion of, a garment on a hook equipped clothes hanger, and comprising similarly shaped front and back pieces positioned one in front of the other and having their side margins and the outer portions of their top margins joined together by binding strips of U-shaped cross section and rows or lines of stitching and also having the central portions of the top margins thereof substantially straight and parallel and disconnected to form a slit-like aperture for receiving the hook of the hanger, and a continuous binding strip of U-shaped cross section extending around and in straddled relation with, and connected by a line of stitching to, the aperture defining portions of the front and back pieces, having the portions thereof at the ends of the aperture in overlapped or straddled relation with, and connected by the last mentioned stitching to, the upper ends of the first mentioned binding strips, and serving to reinforce the last mentioned portions of the front and back pieces and also to prevent rupture of the protector at the ends of the aperture.

GEORGE ARANOW.
